UNITED STATES PATENT OFFICE.

EDWARD C. WALTER, OF NEW YORK, N. Y., ASSIGNOR TO HARRY T. AMBROSE, OF ORANGE, NEW JERSEY.

CALCULATOR.

1,362,550.

Specification of Letters Patent. Patented Dec. 14, 1920.

Application filed December 8, 1916. Serial No. 135,827.

To all whom it may concern:

Be it known that I, EDWARD C. WALTER, a citizen of the United States, residing at New York, in the county of New York and

5 State of New York, have invented certain new and useful Improvements in Calculators, of which the following is a specification, reference being had therein to the accompanying drawing.

10 This invention relates primarily to calculators and has reference more particularly to calculating machines for typewriters.

One of its objects is to provide mechanism that will, when items are written by 15 the typewriter, simultaneously effect an actuation of a plurality of selecting-mechanisms in the calculating machine, after which these items are transferred to denominational members in the machine.

20 Another object is to provide in a single machine a general selecting-mechanism combined with a plurality of sets of secondary selecting-mechanisms so connected to the general selecting-mechanism that operation 25 of one of the secondary selecting-mechanisms will also effect operation of the general selecting-mechanism without operation of the other secondary selecting-mechanism.

Another object is to provide means in such 30 a machine whereby the operation of the general selecting-mechanism may be effected independently of the other selecting-mechanisms therein.

Still another object is to provide in such 35 a machine selecting-mechanism which is not necessarily coupled with computing-mechanism.

A still further object is to provide mechanism which will enable additive computations to be accomplished on one register of 40 a series and subtractive computations on another thereof.

Other objects within the contemplation of my invention are to provide for flexibility 45 of operations in connection with adding, subtracting, zero-producing, elimination of wrong selection without operation of the denominational members or figure-rolls, etc.; and, for these purposes, to incorporate mechanism which is simple in construction, positive in action, and easy of operation; since 50 all of these are of prime importance for producing a commercially perfect and practical machine of the type known as the 55 "bookkeeping machine" wherein debits,

credits, net-sales, old and new balances, etc., are recorded by the typewriter and coöperatively computed by the calculating machine attached thereto.

Other objects and advantages of the invention will be more or less apparent, while further objects and advantages will be made to appear in the following description and in the appended drawings.

In order that the invention may be more 65 readily comprehended, I have exhibited two embodiments of the same in the accompanying drawings which are, however, merely illustrative and constitute an exemplification of a practical structure; and in these— 70

Figure 1 is a view in side elevation of a calculating machine in which my invention is incorporated and shows, in general, the side of the machine on which the actuating handle is mounted and the relative position 75 of the connecting shafts for the different selecting-mechanisms; also, the adding and subtracting shift-lever, the zero-producing lever, etc.;

Fig. 2 is a view in vertical section of the 80 calculating machine and (in fragmentary form) of the carriage on which the master-actuator is mounted;

Fig. 3 is a view in perspective and somewhat diagrammatic, and shows the connection between similar units of a plurality of selecting-mechanisms;

Fig. 4 is a detached view, in side elevation, of one of the selecting-mechanism-units forming a part of the general register, and 90 shows the locking-lever thereof and its latch in inactive position;

Fig. 5 is a similar view and shows the locking-lever and its latch in active position; 95

Figs. 6, 7, 8 and 9 are views in detail of unassembled parts of the structure;

Fig. 10 is a view in horizontal section of the lower part of a plurality of the registers and shows the connections between the 100 various selecting-mechanisms thereof;

Fig. 11 is a fragmentary view in perspective, similar to Fig. 3, of a second set of the components of the selecting-mechanism, the connecting shafts thereof in this instance 105 being disposed below the plane of the actuating plungers; and

Fig. 12 is a fragmentary view in side elevation of a modified form of construction.

The present invention contemplates the 110

employment of the structure of a calculating attachment similar to that disclosed in United States Letters-Patent No. 1,224,872, granted May 1, 1917, and certain details of which also appear in my pending application filed September 11, 1916, Serial No. 119,500, and also in my United States Patent No. 963,927, granted July 5, 1910:

The machine as revealed in my said Patent 1,224,872 includes a series of typewriter-keys—one of which therein appears and is marked 1—mounted (in this instance) on a carriage C which is moved in relation to the calculating-machine CM. Adapted to be operated by the key 1, through connecting actuating-instrumentalities, is a master-actuator 2 which is also mounted on and carried by the carriage C. This actuator, when the key is depressed, is made active to operate certain parts presently to be described and thereby set up a condition on selecting-mechanism constituting one of the primary components of the calculating-machine, and from which the items set up on said selecting-mechanism are transferred to denominational-members or rolls R. In other words, the effect of the operation of, first, the key 1, then of the actuator 2, and then of the selecting-mechanism is to produce an actuation of said selecting-mechanism equal in units to the value of the denomination represented by the depressed key, whereupon an actuating mechanism (presently again to be referred to), such as a pull-handle or motor, is operated to cause the computing-mechanism to be brought into coöperative connection with the selecting-mechanism, this being accomplished while the selecting-mechanism is being returned to normal position. This action will cause the computing-mechanism to be operated to the extent of the return movement of the selecting-mechanism, after which the selecting-mechanism is disconnected from the computing-mechanism. The computing-mechanism is disconnected from the selecting-mechanism, as just referred to, before operation of the carrying-mechanism which also forms a component of the machine. In this instance, however, the computing mechanism is retained in connection with the selecting-mechanism until after the carrying operation is complete; and this involves a certain change of operation, in the machine of the present embodiment, from that produced in the machine of my aforementioned patents and application.

The machine, as herein disclosed—like the machine of my said Patent No. 1,224,872—includes the typewriter-key 1, supported in the carriage C and adapted to control the operation of the master-actuator 2. The actuator, by means of a device presently to be explained, actuates and controls the ex-

tent of movement of a selector-segment 3, constituting a component of the selecting-mechanism, and disposed in coöperative connection with a main gear 4 through a shiftable gear-carrying plate 5. This plate 70 carries a pair of gears 6, and a single gear 6^a. According to the position of the plate 5, the gears 6 or the gear 6^a will be in mesh with the main gear 4. When the carrying-mechanism—represented in this instance by 75 the numeral 7, and which is more fully described in my aforementioned application, Serial No. 119,500—is being operated, the segment 3 will (by mechanism presently to be described) be moved one unit-space beyond its normal position and will then abut against a stop-element 8 which, in turn, will operate to restore the segment 3 to its normal position after it shall have been disconnected from the actuated parts of 85 the computing-mechanism. The segment 3, being in operative connection with the figure-roll R (through the gears 6 or gear 6^a and the main gear 4) until after a computation has been effected and is complete, 90 prevents overthrow of the parts. The foregoing structure is adjunctive to the devices constituting the subject-matter of the present application.

The present improvement contemplates a 95 machine which includes a general register and also a plurality of secondary registers, each of which is coöperatively connected to the general register in such manner that operation of the selecting-mechanism of one of 100 the plurality of secondary registers will also effect a similar operation of the selecting-mechanism of the general register: In Fig. 10, there are represented, at the left of the sheet, two of the secondary registers; 105 on the extreme right is a general register; and between the secondary and general registers is a selecting-mechanism unconnected to any computing-mechanism.

The aforementioned operation of one 110 register by another is accomplished in the following manner: A unit-plunger 9 for each secondary register is disposed in engagement with a mutilated gear 10 mounted on a shaft 11. This shaft carries a gear 12 115 which meshes with the rack-portion of a unit-plunger 13 of the general register. Similarly, the corresponding "tens"-plungers are connected in series to the "tens," 120 plungers of the general register; and so on for the "hundreds," "thousands," "ten-thousands," etc. For the sake of compactness, some of the shafts and gears are disposed above the plungers, as appears in Figs. 2 and 3, while others are disposed below the plane of such plungers, as shown in Fig. 11. The gear 10 of each plunger 9 is provided with a projection 14 which engages a shoulder 15 on its respective plunger and is so shaped that any rearward movement of 130

the plunger will turn the gear 10 and cause rotation of its shaft 11 and, thereby, of the gear 12. As the gear 12 meshes with the rack-edge of the plunger 13 in the general register, movement of such gear will effect a corresponding movement of the plunger 13. The gears 10 and plungers 9 for all the registers—except those for the general register when in normal position—are normally 10 unconnected except where the projection 14 engages the shoulder 15. This arrangement permits normal rotation of the shafts 11 by movement of the plungers 13 of the general register without disturbing the plungers 9 of the secondary registers; and, likewise, movement of the shafts 11 can be effected by action of the plungers 9 of one of the secondary registers without disturbing the plungers 9 of the other secondary register, 20 though the plungers 13 of the general register would, in this instance, be operated.

It will be clear, therefore, that if a selection—represented in the numerals "185," for instance—is made on the first secondary register, the action of its plungers 9 on the connecting shafts 11 and gears 10 and 12 will be to produce a similar selective condition on the general register. Then, by operation of a pull-handle 16 (Fig. 1) the 0 selections will be transmitted to and retained by both registers; and the plungers 9 and 13 will be returned to normal position. Now, if a selection of, say "155" is similarly made on the second register of the 5 series, it follows that a similar selection will be made on the general register; and, by operation of the pull-handle, then, this amount is transferred and retained in the second of the secondary registers and is 0 then transmitted and added to the first amount received by the general register. Thus, the amount of "185" will show on the first register, the amount of "155" will show on the second register, and the amount of 15 "340" will show on the general register.

It is to be understood that the several registers may be independently set for additive or subtractive computations according to the position which a lever 17 is given by 50 the operator—all as more fully explained in my aforementioned Patent No. 1,224,872.

As shown in Figs. 2, 3, and 5, the rear portion of each plunger 13, for the general register, is provided with a stop 18 adapted 55 to engage an abutment 18^a at the rear of the structure. This will prevent the plungers from being moved beyond their normal shiftable position.

The plunger 13 comprises, in this instance, 60 two members, the rear portion being marked 13, as already specified, and the forward portion being marked 19. The forward member 19 is connected to the rear member 13 by means of headed pins or rivets 20 carried by 65 the member 19 and extending through slots

21 in the member 13, this arrangement permitting relative motion between the two members except when locked together by instrumentalities presently to be described. This two-membered plunger 13, 19 is adapted 70 to be engaged by the master-actuator 2 and thereby be thrust rearwardly, and by which the gears 12 and the shafts 11 are rotated in a counterclockwise direction. As the forward end of the member 19 is connected to the selector-segment 3, movement of the two-membered plunger will actuate the segment not only to an extent corresponding to the denomination of the typewriter-key which has been depressed to operate the 75 master-actuator 2 but one additional unit-space when a carrying operation is taking place. When such operation occurs, means are provided whereby the two members 13 and 19 are locked together while a selection 80 is being made thereon, but these are normally unlocked and the forward member 19 is capable of a slight movement—equal to one unit-space—Independently of the member 13 when the carrying operation is taking place. The segment 3 will cause the forward member 19 to be moved this extra unit-space during the carrying operation, and the stop 8 will actuate and return the segment and the forward member to normal position 85 after the carrying operation shall have been completed. This action takes place only on the plungers 13 of the general register, since the shoulders 15 of the plungers 9 may disengage from and reengage with the projections 14 on the gears 10 without effecting movement either of these gears 10 or of the gears 12 and the shafts 11 therefor. It will, of course, be understood that the actuator 2 is adapted to engage the forward ends of the plungers 9 to rotate the gears 10 and shaft 11, and whereby the gears 12 and plungers 13 are similarly actuated.

The means for locking the members 13 and 19 together include a locking-lever 22 mounted on the member 19 and which, when raised, will position a lug 22^a thereon into a recess 22^b in the member 13 and, then, lock the members 13 and 19 together, as shown in Fig. 3. When the lever 22 is in its lowered position, as shown in Fig. 4, the members are unlocked and this permits them to be shifted relatively.

The structure for operating the computing mechanism aforementioned, includes a shaft 23 which (by mechanism interposed between it and the pull-handle 16) is given a complete revolution each time that the pull-handle is operated. Also mounted on this shaft is a gear 24 with which meshes an intermediate gear 25. With this meshes a gear 25^a which, in turn, meshes with a gear 26 which, through the shaft 23 and gears 24, 25 and 25^a, will also be given a complete revolution each time that the pull-handle is 125 130

actuated. Attached to the gear 26 is a cam-element 27 provided with a circumferential projection 28. Disposed below the locking lever 22, and adapted to tilt the same upwardly is a plate 29 provided with a flange 30 upon which the several locking levers 22 rest. The plate 29 is fulcrumed on a shaft 31 which carries an arm 32 adapted to engage with the periphery of the cam-element 27. 5 A spring 29^a is adapted to hold the arm 32 against the cam-element. In consequence, when the handle 16 is operated, the cam-element will make one complete revolution and, when the arm 32 rides off the projection 28, 10 the plate 29 will be permitted to descend and allow the locking-levers 22, under the action of springs 33, to drop, and, then, to raise the plate 29 and latches 22 after the carrying operation has been completed. This carrying operation, as aforementioned, causes the 15 forward member 19 of the two-membered plungers to be moved one space beyond the normal position and then be returned by the temporary stop 8 to normal position. 20 The rear members 13 of the two-membered plungers are provided with latches 34 which are adapted to rest against and be held in a raised position by the locking-levers 22. Springs 35 which engage the latches 34 will 25 cause them to be lowered when the locking-levers 22 are dropped. The latches 34 project through a supporting comb 36 and are provided with shoulders 34^a adapted to hook over the comb, this construction and arrangement preventing movement of the rear member of the two-membered plungers when the latches 22 are in their lowered position, and this permits the member 19 to be moved in 30 either direction without disturbing the rear member of the two-membered plunger. 35 A modified form of structure (as shown in Fig. 12) contemplates the omission of the projection 19^a on the member 19 and of the spring 33, and the inclusion of a transverse bar 37. This bar is so disposed as normally to be clear of the ends of the locking-levers 22 when they are in their normal position; but such levers (when the member 19 is shifted rearwardly) are moved rearwardly 40 and over the bar 37 when a selection is being made so that the bar will then hold the locking-levers 22 in locked position until they are returned to normal position where the latches 34 will cause these levers to be lowered and the plate 29 will again tilt the levers to locking position and hold them therein until another selection is made. The function of the bar 37 is to prevent the locking-levers 22 from dropping—when the lifting-plate 29 is lowered—until after the plungers shall have been returned to normal position. This insures the proper return of the rear members of the two-membered plungers to normal position. 45 50 55 60 65

Obviously, registers which contain six

units will be provided with six connecting shafts; while a register which is composed of nine units will have a corresponding number of connecting shafts, etc.

From the foregoing, it will be perceived 70 that I have succeeded in devising a structure which is well adapted to achieve the several objects and ends in view. It is quite simple and compact in form, and the parts of which it is formed are readily manu- 75 factured and assembled.

As many changes can be made in the above construction and many widely different embodiments of the invention can be made without departing from the spirit 80 thereof, it is intended that all matter contained in the foregoing description and shown in the accompanying drawings shall be interpreted as illustrative and not in a limiting sense. 85

What I claim is:

1. In combination with a typewriter including keys and a carriage movable step-by-step by the action of the keys, a plurality of computers, each provided with selecting 90 means and severally operated to effect a selection by the action of the keys, and normally independent means comprising a series of mutilated gears and a full gear all secured together for connecting and disconnecting the corresponding components of each selecting means to effect a simultaneous selection on two of the computers when the selecting means of one of the computers is operated by the keys and merely a selection 95 on one of the computers when the selecting means of another of the computers is operated by the keys. 100

2. A typewriter including keys and a carriage moved step-by-step by the operation of 105 said keys, a plurality of relatively stationary computers, each provided with selecting mechanisms severally operated by the keys to effect a selection, and normally inactive means comprising mutilated and full gears 110 for connecting and disconnecting corresponding components of the selecting mechanisms of the computers when the selecting mechanism of one of the computers is operated and, thus, effecting a selection on a plurality 115 of the selecting mechanisms, such means remaining unconnected when the selecting mechanism of one of the computers is operated by the keys and, thus, effecting a selective operation on merely one of the selecting mechanisms. 120

3. A typewriter including operating keys, a carriage moved in a step-by-step manner by the operation of the keys, and a plunger on the carriage having a differential 125 movement under the action of such keys, a plurality of normally stationary computers, each provided with a series of selecting mechanisms adapted to be actuated variable degrees by the action of the keys through 130

the medium of the plunger, normally independent means for effecting simultaneous operation of a plurality of the selecting mechanisms of the computers when the selecting

5 mechanism of one of the computers is operated by the plunger and effecting merely a selection on the selecting mechanism on one of the computers when a selecting mechanism of another of the computers is operated by the plunger, and means for returning the selecting mechanisms to normal position and effecting a disconnection of the selecting mechanisms.

4. A typewriter including a carriage, in combination with a plurality of computers, selecting mechanisms therefor, means comprising a series of gears normally disconnected from and operable independently of some of the selecting mechanisms for 20 connecting the selecting mechanism of certain of the computers and without operating the selecting mechanisms of other of the computers and operating automatically to connect a plurality of the selecting mechanisms of the computers for simultaneous operation thereof when the selecting mechanism of another of the computers is operated.

5. A typewriter including operating keys, a carriage actuated in a step-by-step manner by the operation of the keys, a single reciprocating master means mounted on the carriage and having a differential movement under the action of the keys, a plurality of 35 computers juxtaposed to the carriage and each including a series of selecting devices actuatable to variable extents by the operation of the master means to effect merely a selection, means comprising a series of mutilated and full-toothed members juxtaposed to the respective selecting devices and normally independent of all but one of the devices, said means being operable to effect simultaneous operation of the selecting devices of two of the computers when any but one of such devices is operated, only one of the selecting devices being operated when said excepted device is operated, and separate means for returning all of the devices 50 to normal position, said returning operation effecting a single or a double computation in the computers according to the selections made and, also, simultaneously disconnecting the connected selecting devices if a plurality selection has been made.

6. A computing structure including a plurality of computing devices, a series of selecting mechanisms in the computing devices, an independent series of selecting 60 mechanisms, all of the selecting devices being normally unconnected one from the other, means comprising a series of mutilated and full-toothed members adjacent the respective selecting devices for connecting the corresponding components there-

of to effect simultaneous operation of the same when one of the devices is operated and permitting operation of a single device when other of the devices are operated, and means for returning the selecting devices to normal position and effect a computation in the computers and simultaneously disconnect any of the selecting devices which had been connected in the operation of making a selection. 75

7. In a computing structure, a series of key-operated rack-bars, some of the bars being provided with an incut at the rack provided end thereof, a shaft extending transversely of the bars and provided with 80 toothed members, projections formed on some of the toothed members and normally abutting against the bars at the incut portion, the other toothed members being in mesh with the rack portion, the teeth of the 85 toothed members being out of engagement with the racks when the projections are abutting against the incut portions of the racks of the other bars.

8. A computing machine including a 90 series of selecting devices, a portion of each of the selecting devices comprising a plurality of separably movable bars, a latch for joining the bars to prevent independent movement thereof, keys for moving the bars 95 simultaneously in one direction, and means for actuating the bars in the opposite direction during a part of their movement and actuatable to release the latch and thereby permit independent movement of the bars during a continued movement thereof.

9. In a computing machine, selecting mechanisms, a part of which comprises a two-membered rack bar, the members thereof being slidably connected together, one of 105 the members being provided with a notch, and a latch on the other member adapted to enter the notch to prevent relative movement of the members, a spring for each latch to move it out of the notch, a lifting 110 plate common to the latches of the selecting mechanisms and actuatable to move the latches into the notches, and actuating means for operating the lifting plate.

10. A computing machine including a 115 plurality of unit-transfer mechanisms, a general transfer mechanism, normally unconnected means automatically operated by actuation of the unit-transfer mechanisms to connect any of the plurality of the transfer 120 mechanisms to the general transfer mechanism and thereby cause simultaneous operation of such general transfer mechanism, the normally unconnected means remaining inoperative when the general transfer mechanism is operated. 125

11. In combination, a computer, a typewriter for operating the same, a series of secondary registers, a general register associated therewith, a series of shafts therein, 130

gears on the shafts meshing with the general register, mutilated gears also on the shafts and normally out of mesh with the secondary registers, and automatically operated 5 means for causing the mutilated gears to mesh with the secondary registers when operated by the typewriter.

12. The combination with a typewriter comprising keys, of a series of secondary 10 registers, a general register, a series of mechanisms for each register and movable variable distances by the keys, a shaft provided for each set of corresponding mechanisms of the registers, a mutilated gear for each corresponding mechanism of the series of registers, and a complete gear for the corresponding mechanism of the general register.

13. The combination with typewriter-keys, of a series of secondary registers and a 20 general register associated therewith, a lever for each register movable variable distances by the typewriter-keys, gear-teeth and a shoulder on each lever of the series, gear-teeth on the levers of the general register, a 25 shaft for each set of corresponding mechanisms of all of the registers, a gear provided with a projection mounted on the shaft for each of the corresponding mechanisms of the series of registers, the projection resting 30 against the shoulder of the levers and operable to initiate movement of the shaft when the levers are moved, and a gear mounted on the shaft and constantly in mesh with the lever of the general register.

14. The combination with a computing typewriter having keys, of a series of secondary registers and a general register associated therewith, a series of selecting mechanisms for each register and settable by the 40 keys to effect a selective-action, a series of shafts associated therewith, and a complete gear and a series of mutilated gears on the shafts for transmitting motion from corresponding units of the selecting mechanisms 45 of the series of registers to those of the general register whereby a simultaneous selection will be made by action of the typewriter-keys on any one of the registers of the series and on the general register.

15. The combination with a computing typewriter including keys, of a plurality of series of plungers movable variable distances by the keys, each plunger being provided with gear-teeth and a shoulder, shafts extending 55 across the plungers and provided with mutilated gears against which the shoulders of the plungers abut and with which the teeth of the same mesh, a general register comprising a series of two-membered plungers, one member of which is provided with gear-teeth, gears on the shafts for meshing with the gear-teeth, locks on the plungers for locking the two members of each plunger together, and means for operating the locks.

16. The combination with a computing-

70 typewriter including keys, of a series of selecting-mechanisms associated therewith, one of said series being of a construction different from the others and one part of the same having movement at certain periods independently of its conjoined parts, and means for locking the conjoined parts together.

17. The combination with a typewriter, of a series of calculating-machines each including 75 selecting-mechanisms normally unconnected one with the other and actuatable by the typewriter, means for operating certain of the selecting-mechanisms while the typewriter is rendering active other of the selecting-mechanisms and while certain of the selecting-mechanisms are inactive.

18. The combination with a typewriter, of a series of calculating-machines operable thereby independently or in series and each 85 including selecting-mechanisms normally unconnected one with the other, and means for connecting a series of the selecting-mechanisms and effecting their operation while the typewriter is operating certain of the calculating-machines; the connecting and operating means being inactive as to certain 90 of the selecting-mechanisms when the typewriter is operating other of the calculating-machines either independently or in series. 95

19. The combination of a typewriter and the printing-keys therefor, of a calculating machine including a plurality of registers associated therewith, a selecting-mechanism for each register operable by the printing-keys to effect a selection, and means for effecting a simultaneous movement of a plurality of the selecting mechanisms independently of the operation of the registers for effecting a computation; said means 100 comprising a series of mutilated gears for all but one of the selecting-mechanisms, one of the selecting-mechanisms being provided with a series of full-toothed gears, the mutilated gears being normally out of mesh 110 with their respective selecting-mechanisms and the full-toothed gears being normally in mesh with their respective selecting-mechanisms.

20. The combination with a typewriter, 115 the printing-keys thereof, and a master-actuating means operated thereby, of a plurality of registers co-operatively associated with the typewriter, means associated with each register and adapted to be successively 120 operated by the master-actuating means, and means for simultaneously operating a plurality of the said successively-operated means when operated by said master-actuating means; said means comprising a series 125 of mutilated gears for all but one of the selecting-mechanisms, one of the selecting-mechanisms being provided with a series of full-toothed gears, the mutilated gears being normally out of mesh with their re- 130

spective selecting-mechanisms and the full-toothed gears being normally in mesh with their respective selecting-mechanisms.

21. The combination with a typewriter-operated computing-machine, of a typewriter including keys, a series of registers, denominational selectors associated therewith and settable by the typewriter-keys prior to the actuation of the registers for effecting a computation, and means for simultaneously actuating a plurality of the key-set selectors; said means comprising a series of mutilated gears for all but one of the denominational selectors, this denominational selector being provided with a full-toothed gear, the mutilated and full-toothed gears for like denominational selectors being fastened together.

22. In combination in a computing-machine, of a plurality of unit-transfer mechanisms and a general-transfer mechanism, any one of the plurality being operable to cause simultaneous operation of the general-transfer mechanism independent of operation of other of the transfer mechanisms; each of the unit-transfer mechanisms being associated, but normally out of mesh, with a toothed element and the general-transfer mechanism being associated but normally in mesh, with a toothed element.

23. The combination with a typewriter having keys, of a plurality of computing-heads associated therewith, a set of denominational devices therein movable variable distances by action of the typewriter-keys thereon, a general computing-head, a set of denominational devices therein and also movable variable distances by action of the typewriter-keys thereon, and means connecting corresponding denominational devices of each set and the general computer set whereby movement of any of the denominational devices will cause simultaneous movement of the corresponding device in the general set, and movement of the general set may be accomplished by action of the typewriter-keys without movement of the other sets.

24. In combination, a typewriter having keys, a computing-machine including a series of secondary registers and a general register, a series of selecting-mechanisms for each register movable variable distances by the keys of the typewriter, a series of tens-carrying mechanisms for the registers, a shaft for each set of corresponding selecting-mechanisms, a mutilated gear on the shaft for each corresponding selecting-mechanism, and a complete gear on the shaft for the corresponding mechanism of the general register, said mutilated and complete gears operating to effect a simultaneous operation of a plurality of selecting-mechanisms when any of the series of secondary registers is op-

erated and permitting operation of the general register without operation of the secondary registers, and means for causing the tens-carrying mechanism to move the selecting-mechanisms one unit-space beyond normal position independently of the movement of the shafts.

25. The combination with a typewriter, of a computing-machine acting under the influence of the typewriter and including an actuating-lever and a plurality of series of selecting-mechanisms, a series of shafts normally unconnected with the selecting-mechanisms, means for connecting the shafts to the selecting-mechanisms to effect conjoint operation thereof in one direction by operation of the typewriter and in the opposite direction to normal unconnected position by operation of the actuating-lever.

26. The combination with a typewriter, of a computing-machine acting under the influence of the typewriter and including an actuating-lever and means operated thereby for effecting computations, a plurality of series of selecting-mechanisms normally unconnected one from the other, means operated by the typewriter for connecting the selecting-mechanisms, and means operated by action of the actuating-lever to effect movement of the selecting-mechanisms to produce a plurality of computations and also to effect disconnection of conjoint selecting-mechanisms, whereby the same may then have independent movement.

27. The combination with a typewriter, of a computing-machine including an actuating-lever and means operated thereby for effecting computations, a plurality of series of selecting-mechanisms normally unconnected one from the other, means operated by the typewriter for connecting the selecting-mechanisms, means operated by action of the actuating-lever to effect movement of the selecting-mechanisms to produce a plurality of computations and also to effect disconnection of conjoint selecting-mechanisms, whereby the same may have independent movement, and means operated by the actuating-lever for effecting independent movement of the selecting-mechanisms.

28. The combination with a typewriter-operated computing-machine, of a plurality of series of independently operable selecting-mechanisms, keys for effecting movement of the same in one direction, an actuating-lever for effecting movement thereof in the opposite direction, and normally unconnected means for connecting the selecting-mechanisms in pairs when operated by the keys and operating to effect disconnection of the mechanisms and independent movement of the same by operation of the actuating-lever.

29. The combination with a typewriter

- having keys, of a computing-machine including a plurality of series of selecting-mechanisms movable in one direction by operation of the typewriter keys to effect a selection only, normally unconnected means juxtaposed to the selecting-mechanisms for connecting and operating a plurality of the same when some of them are operated by the keys and continuing unconnected even when other of the selecting-mechanisms are operated, means for moving said selecting-mechanisms in the opposite direction to effect either a single computation or a plurality of computations and to effect disconnection of connected selecting-mechanisms and thereafter to permit independent movement of the selecting-mechanisms, and means for effecting such independent movement of the mechanisms.
30. The combination with a typewriter, of a computing-machine including actuating-means, a plurality of series of selecting-mechanisms comprising components of relatively different construction, means normally unconnected for connecting the selecting-mechanisms in pairs for conjoint movement under predetermined conditions of manipulation and also independent operation under other conditions of manipulation, means operated by the actuating means for returning the selecting-mechanisms to normal unconnected position, and means for effecting independent action of the selecting-mechanisms.
31. The combination with a typewriter, of a computing-machine including actuating-instrumentalities, selecting-mechanisms operable by the typewriter to effect a selection, and comprising two-part plungers, a lock carried by one part of the plunger for connecting the two parts together, spring-actuated levers connected to the other part for effecting disconnection of the lock and for holding one of the plunger-parts from movement when released, and means operable by action of the actuating-instrumentalities for rendering the lock active to lock the plungers together.
32. The combination with a typewriter having keys, of a computing-machine including actuating-instrumentalities, and selecting-mechanisms settable by operation of the type-writer keys to effect a selection and also a connection of a plurality of the selecting-mechanisms and operable by operation of the actuating-instrumentalities to effect computations and a disconnection of the selecting-mechanisms.
33. The combination with a typewriter having keys, of a computing-machine including actuating-instrumentalities, selecting-mechanisms settable by operation of the typewriter-keys to effect a selection and also a connection of a plurality of the selecting-mechanisms and operable by operation of the actuating-instrumentalities to effect computations and a disconnection of the selecting-mechanisms.
34. The combination with a typewriter having keys, of a computing-machine including actuating-instrumentalities, a plurality of series of selecting-mechanisms positionable by operation thereon of the typewriter-keys, a plurality of series of tens-carrying mechanisms operable by action of the actuating-instrumentalities through the medium of the selecting-mechanisms, means operable by action of the actuating-instrumentalities to effect movement of the selecting-mechanisms by the tens-carrying mechanisms, and means for restoring said parts to normal position.
35. The combination with a typewriter, of a computing-machine comprising a plurality of series of selecting-mechanisms, shafts extending across, above and below the selecting-mechanisms, full-toothed and mutilated gears on the shafts for connecting the selecting-mechanisms for conjoint movement, the mechanisms also having independent movement thereof, and means for moving the selecting-mechanisms to normal position and thereafter permitting their independent movement.
36. The combination with a typewriter, of a computing-machine comprising a selecting-mechanism consisting of a plunger involving two members slidably held together, a spring-actuated latch for holding one member of said plunger stationary, a lock-latch attached to the other member of the plunger for locking the two members together and for releasing the same, and means for controlling movement of the lock-latch.
37. The combination with a typewriter provided with keys, a plunger movable variable distances thereby, a latch on the plunger, and means operated by the keys to lift the latch, of a computing-machine including a plurality of series of selecting-mechanisms operable by the plunger through the medium of the keys, means normally unconnected but operable by action of the plunger to connect a plurality of selecting-mechanisms whereby the same may have conjoint movement, said latch operating to connect the selecting-mechanisms with the plunger when operated by the keys to prevent the selecting mechanisms from shifting away from the plunger and having movement away from the selecting-mechanisms prior to the return movement of the plunger to normal position.
38. The combination with a typewriter, of a computing-machine comprising selecting-mechanisms, plungers formed of a plu-

rality of elements, serrated racks for slid-
ably retaining the elements, stops on one
element of the plunger for abutting against
the racks, a spring-actuated latch on the
same element movable to latch over the
racks and hold the plunger from movement,
a lock-latch on the other element of the
plunger for locking the two elements to-
gether, and means for locking and releasing

the lock-latch and for moving the spring- 10
actuated latch.

In testimony whereof I affix my signature
in presence of two witnesses.

EDWARD C. WALTER.
